BAKERY SHOWCASE

Gilbert W. Hutchcraft, Winamac, Ind.

Application December 28, 1955, Serial No. 39,507

Term of patent 3½ years

(Cl. D80—11)

Fig. 1.

Fig. 2.

Fig. 3.

Fig. 1 is a front perspective view of a bakery showcase embodying my new design; the rear being substantially the same as the front except for the recessed base and the tapered front;

Fig. 2 is an enlarged front elevational view thereof; and

Fig. 3 is an end elevational view of Fig. 1, the other end being the same as the one shown.

I claim:

The ornamental design for a bakery showcase, as shown and described.
